HOLDER AND DISPENSER

Maurice J. Fletcher, Des Moines, Iowa, assignor to
 Cadet Smoke Stands Company, Des Moines,
 Iowa

Application May 22, 1942, Serial No. 444,098

1 Claim. (Cl. 312—73)

The principal object of this invention is to provide a holder and dispenser which may be used for holding cigarettes or other items and which is economical in manufacture and pleasing to the eye.

A still further object of this invention is to provide a holding and dispensing unit which is versatile in its adaptation and which lends itself to rapid production.

A still further object of this invention is to provide a holder for cigarettes, matches, and the like, which may be quickly and easily fabricated and assembled.

A still further object of this invention is to provide a holder for cards, sheets, plates and the like upon which may be carried information of advertising value displayed thereby.

These and other objects will be apparent to those skilled in the art.

My invention consists in the construction and arrangement and combination of the various parts of the device, whereby the objects contemplated are attained as hereinafter more fully set forth, pointed out in my claim and illustrated in the accompanying drawing, in which:

Fig. 1 is a front elevational view of my dispenser ready for use.

Fig. 2 is a side elevational view thereof; and

Fig. 3 is a top elevational view of my holder and dispenser.

The principal utilities of my device comprise a structure of the device, its adaptability to various items of merchandise, its ornamental appearance, and its advertising value. Such principal points will hereinafter be more fully set forth.

Referring to the drawing I have used the numeral 10 to indicate a base having cut therein the longitudinal grooves 11 and 12 as shown in the drawing. The numerals 13 and 14 indicate two frame members having their miter portions abutting at 15 as shown in Fig. 1.

The numerals 16 and 17 indicate grooves or key slots cut in the frame members 13 and 14 respectively, adjacent the miter joint 15. The numerals 18 and 19 indicate grooves cut in the frames 13 and 14, spaced from each other and opening upwardly. Into these grooves 18 and 19 are placed plates 20 and 21, respectively, forming a receiving trough or opening therebetween to receive cigarettes 22 or similar articles. These plates 20 and 21 may be permanently or detachably mounted. It will here be noted that the space between the plates 20 and 21 can be varied according to the type of merchandise to be dis-

pensed such as cigarettes, cigars, toothpicks, and many other articles and the plates 20 and 21 can have advertising material on their outer faces, pictures and the like and these plates 20 and 21 may be constructed of many suitable sheet materials.

To secure the two frame members 13 and 14 together and to hold them on the base 10 I have provided the key members 23 and 24. These key members are placed within the grooves 11 and 12 and the grooves 16 and 17 as shown in the drawing, thereby, holding the V shaped frame together at the miter joint 15 and supporting the frame on the base 10.

15 The numeral 25 indicates a holding slot cut in the members 23 and 24 for holding a book of matches, menu, placard, or similar article.

The practical operation of my device is as follows:

The base is fabricated with the slots 11 and 12 therein, and the frames 13 and 14 are placed together after which the key members 23 and 24 are placed in position. These key members may be glued in place or may be a friction fit for attachment to permit the article to be disassembled for shipment. It will here be noted that any form of keys may be used and while this particular method is particularly adaptable to commercial production any type of holding

30 means may be substituted for the keys 23 and 24 which will adequately support the frame on the base 10. When the two members 20 and 21 are placed close together and constructed of a transparent material the device may be used as a picture frame. When used as a dispenser the cigarettes or other items are conveniently placed so that they may be lifted out one at a time and the device will still retain its ornamental balance and design. Any suitable material may be

40 used for the construction of the device and it may be made of plastic, wood, metal, glass or other material, and may be even cast as a single unit or in multiple parts out of such material. The frame members 13 and 14 may be placed 45 together in such a fashion as to form a V shape as illustrated in the drawing or in any other appropriate manner.

Thus it will be seen that I have provided a holder and dispenser which fulfills all my objects, that is versatile in its use, permits the adequate display of advertising matter and one which is simple to manufacture.

Some changes may be made in the construction and arrangement of my improved holder and dispenser without departing from the real

spirit and purpose of my invention, and it is my intention to cover by my claim any modified forms of structure or use of mechanical equivalents which may be reasonably included within their scope.

I claim:

A device having a flat top base member, spaced parallel grooves in the upper surface of the base, vertical plate like elongated keys fitted in the

grooves, a frame having a V-shaped bottom, placed transversely across said keys, with the apex of the V between the keys, said bottom having grooves on its underside receiving said keys, the upper surface of said bottom having spaced parallel grooves transverse of said keys, and vertical plates in said last named grooves.

MAURICE J. FLETCHER.
